PHONOGRAPH CABINET

Carl W. D. Schaefer, Dayton, Ohio, assignor to
Philco Corporation, Philadelphia, Pa., a cor-
poration of Pennsylvania

Application September 29, 1948, Serial No. 148,872

Term of patent 3½ years

(Cl. D56—4)

To all whom it may concern:

Be it known that I, Carl W. D. Schaefer, a citizen of the United States, residing at Dayton, in the county of Montgomery and State of Ohio, have invented a new, original, and ornamental Design for a Phonograph Cabinet, of which the following is a specification, reference being had to the accompanying drawing, forming part thereof, in which:

Figure 1 is a perspective view of a phonograph cabinet embodying my novel design;

Figure 2 is a fragmentary sectional view taken at line 2—2 of Figure 1;

Figure 3 is a fragmentary sectional view taken at line 3—3 of Figure 1; and

Figure 4 is a fragmentary sectional view taken at the point generally indicated at 4 in Figure 1.

Figures 2, 3 and 4 are drawn on a scale approximately five times the scale to which Figure 1 is drawn.

I claim:

The ornamental design for a phonograph cabinet, substantially as shown.

CARL W. D. SCHAEFER.
